The ornamental designs for a mount for a digital media player, as shown and described.

DESCRIPTION

FIG. 1 is a perspective view of a mount for a digital media player, in an exploded condition.

FIG. 2 is a perspective view of a top, front and right side of the mount of FIG. 1.

FIG. 3 is a front view of the mount of FIG. 1.

FIG. 4 is a rear view of the mount of FIG. 1.

FIG. 5 is a top view of the mount of FIG. 1.

FIG. 6 is a bottom view of the mount of FIG. 1.

FIG. 7 is a right side view of the mount of FIG. 1. Although not separately shown, the left side view is a mirror image of the right side view.

FIG. 8 is a perspective view of a mount for a digital media player, in an exploded condition.

FIG. 9 is a perspective view of a top, front and right side of the mount of FIG. 8.

FIG. 10 is a front view of the mount of FIG. 8.

FIG. 11 is a rear view of the mount of FIG. 8.

FIG. 12 is a top view of the mount of FIG. 8.

FIG. 13 is a bottom view of the mount of FIG. 8; and, FIG. 14 is a right side view of the mount of FIG. 8. Although not separately shown, the left side view is a mirror image of the right side view.
